US00D990444S

(12) **United States Design Patent** (10) **Patent No.:** **US D990,444 S**
(45) **Date of Patent:** **** Jun. 27, 2023**

(54) **ELECTRONIC DEVICE**

(71) Applicant: **Samsung Electronics Co., Ltd.**, Suwon-si (KR)
(72) Inventors: **Jinwoo Lee**, Suwon-si (KR); **Junwon Lee**, Suwon-si (KR); **Namsu Kim**, Suwon-si (KR); **Kangmoon Kim**, Suwon-si (KR); **Jieun Myung**, Suwon-si (KR); **Dahyun Lee**, Suwon-si (KR); **Bosoon Kang**, Suwon-si (KR); **Jiyun Lim**, Suwon-si (KR); **Junho Jin**, Suwon-si (KR)
(73) Assignee: **SAMSUNG ELECTRONICS CO., LTD.**, Suwon-si (KR)

(**) Term: **15 Years**

(21) Appl. No.: **29/812,254**

(22) Filed: **Oct. 20, 2021**

(30) **Foreign Application Priority Data**

Apr. 29, 2021 (KR) 30-2021-0020865

CLAIM

The ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The dashed broken lines in the figures depict portions of the electronic device that form no part of the claimed design.

1 Claim, 6 Drawing Sheets
